UNITED STATES PATENT OFFICE.

ELDEN P. LAMB, OF CAMDEN, MAINE, ASSIGNOR OF ONE-HALF TO JOHN BIRD, OF ROCKLAND, MAINE.

VAPORIZER FOR INTERNAL-COMBUSTION ENGINES.

1,088,664.

Specification of Letters Patent. Patented Feb. 24, 1914.

Application filed December 13, 1912. Serial No. 736,607.

To all whom it may concern:

Be it known that I, ELDEN P. LAMB, a citizen of the United States, residing at Camden, Maine, have invented certain new and useful Improvements in Vaporizers for Internal-Combustion Engines, of which the following is a specification.

My present invention relates to improvements in float feed or constant level carbureters or vaporizers for internal combustion engines.

The invention has among others for its objects to provide an extremely simple construction, capable of being economically produced and easily manipulated to secure proper mixtures for starting and under varying speeds and loads.

With these and other objects in view, the invention includes the novel features of construction and arrangement and combination of parts hereinafter described and particularly defined by the appended claims.

A carbureter embodying my invention is illustrated in the accompanying drawing, in which—

Figure 1 is a side elevation; Fig. 2 is a central vertical section; Fig. 3 is a sectional view of the rotatable member 15. Fig. 4 is a sectional elevation of the valve, and Fig. 5 is a sectional view of the upper part of the carbureter with the valve removed.

Referring by reference characters to this drawing, the numeral 1 designates the float container within which is located a float 2, which provides a constant oil level in the float chamber. This float chamber has a conical bottom 3 provided with openings 3^a, which allow the oil to pass to a chamber 4 formed between the under side of said bottom 3 and a conical wall 5 of thin heat conducting metal carried by the removable bottom 6, which is connected to the container 1 by suitable means, as for instance machine screws 6^a. This bottom is provided with means such as nipples 7 and 8 by which pipes may be connected for securing a circulation of heating fluid within the space between the cone 5 and the bottom 6, such fluid comprising hot water steam or exhaust gases. From the construction thus described it will be seen that the hydrocarbon in the chamber or space 4 is in an extremely thin film or layer, and is readily heated by the heating fluid below the cone.

Rising upward from the conical bottom

3 and preferably integral therewith is a cylindrical member 3^b having an interior valve receiving chamber 3^c. Within this valve chamber works the valve 7' having a conical lower end serving to regulate the amount of hydrocarbon which passes through the contracted fuel opening 3^d. The valve member 7' fits snugly in the lower portion of the chamber 3^c and has a central fuel passage 7^a provided with branch passages or ports 7^b communicating with the conical lower portion of the valve chamber. The passage 7^a in the valve member is designed to be placed in communication with the intake of the engine in the manner hereinafter described, so that the suction of the engine draws the oil up through this passage, the quantity depending on the vertical adjustment of the valve. The upper portion of the valve chamber is enlarged to provide an annular space or channel, as indicated at 3^e, and additional ports or passages 7^c place this annular space in communication with the oil passage 7^a. This annular chamber and passages 7^c are intended for unvariable air supply, and for securing a rich mixture for starting purposes. The valve member 7 is provided at its upper end with an enlarged cylindrical member 8 and an interior centrally arranged cylinder 9 having a bore axially in line with but larger than the passage 7^a through which the rich mixture referred to is drawn. This central member 9 joins the outer cylinder 8 by a bottom flaring wall 9^a, and the cylinder 8 is provided with air ports 10 designed to coöperate with corresponding ports 11^a, 11^b, in the cylindrical wall 11 carried by the portion 12 of the carbureter, which is shown in sectional view in Fig. 5. This has a horizontal extension to one side of the carbureter chamber indicated at 12^a, which is provided at the lower side with cold air inlet ports designed to be covered and uncovered by a movable member 13, and with a hot air inlet port 14 by which hot air may be introduced in the manner common in carbureters. In order to secure the proper adjustments to vary the proportions of oil and air, the cylindrical portion 8 is provided with a handle 8^a by which it may be rotated to bring the ports 10 and 11^a into or out of register, and the said cylindrical member 8 is provided near its upper end with an internal screw thread which is engaged by corresponding screw threads on 11^b.

a rotatable member 15 having a flange 15^a which is rotatably mounted between the sleeve and the member 16, which serves for connecting the carbureter to the engine intake, which is not shown in the present drawing. This member 15 is provided with a handle 15^b by which the same may be rotated, and set screws are provided for adjustably limiting the amount of movement 10 of the levers 8^a and 15^b.

In the operation of the device above described for starting the engine, the lever 8^a is moved into position to close the auxiliary air inlet ports, and the lever 15^b is also 15 moved in the same direction, the movement being to the left or in the direction of the hands of a clock, which raises the valve and gives a rich mixture. Now, with the engine running light or unloaded, if the lever 15^b 20 is swung to the right it varies the position of the needle valve, that is, moves it down until the proper mixture is secured. Thereafter the movement of lever 8^a to the right opens the auxiliary air ports, and at the 25 same time, lifts up the needle valve, giving the motor or engine more fuel.

I find that under some conditions, as for instance, in carbureters or vaporizers for larger engines, that it is desirable to introduce a heated fluid, such, for example, as steam, directly into the mixture, and that it is desirable to admit this in close proximity to the air passages 7^c. In order to accomplish this, the wall of the valve chamber and 30 the conical bottom wall of the hydrocarbon chamber are provided with a passage 16, the part passing through the conical wall 3 being enlarged to form a valve chamber 17, within which works a needle valve 18 for 35 controlling the passage of the steam or the like therethrough. This valve chamber 17 communicates by a port 19 with the heating chamber below the conical member 5 while the upper portion of the passage 16 is adapt- 40 ed to align with the passage 20 in the valve, the arrangement being such that the passage 20 is in alignment with the end of passage 16 only when the carbureter is adjusted for 45 work or, in other words, when the lever 8^a is moved to the right to admit a larger 50 amount of hydrocarbon and air.

A carbureter such as herein before disclosed may be used for light hydrocarbons, such as gasoline, or for heavier hydrocarbons, such as kerosene, as the subjecting of the hydrocarbon to heat while in a widely spread-out and thin film enables its temperature to be raised to such a degree as to secure effective vaporization and a thorough 55 combustion, even if the heavier hydrocarbon be used. Furthermore, as the wall of the valve chamber is integral with the bottom of the float chamber and the valve moves in direct contact with said wall, both said parts 60 are heated by the heating medium. The 65

result of this is that as the hydrocarbon is drawn through the small holes or passages in the valve it is additionally heated; and the air, passing through the annular air space and small air ports, is also heated so 70 that a mixture of heated hydrocarbon and heated air is secured.

In order that either gasoline or kerosene may be fed to the carbureter at will, provision 75 may be made by which either of both may be piped to the carbureter, it being deemed unnecessary to disclose any connection by which this may be done herein.

An important feature of the present vaporizer or carbureter is that by this construction the necessity for the ordinary throttle valve is avoided, as the speed of the engine can be controlled entirely under working conditions by simply manipulating the lever 8^a. The movement of this lever to the 80 right opens the auxiliary air and increases the fuel, thus giving more power or speed to the engine, while the movement of the lever in the reverse direction simultaneously cuts down the fuel and air while maintaining proper proportions, thus acting as a 85 throttle and reducing the power and speed of the engine.

I claim as my invention:

1. A vaporizer for internal combustion 90 engines having a valve chamber with a valve seat and fuel inlet port at its lower end, a cylindrical fuel controlling valve fitting therein having a lower end co-operating with said seat, there being an annular space adjacent said seat between the valve and valve chamber, said valve having its central longitudinal fuel passage communicating by branch passages with said space, said valve chamber and said valve having also between 95 them an air channel, and said valve having branch passages leading from said longitudinal passage to said air channel.

2. A vaporizer for internal combustion 100 engines having a valve chamber with an enlarged upper portion constituting a constant air supply and a conical valve seat at its lower end with a fuel inlet, a cylindrical fuel controlling valve member fitting 105 said valve chamber and having a reduced lower end provided with a conical portion fitting said seat, said valve member having a central longitudinal passage with branch 110 passages leading to the space formed by said reduced portion and other branch passages leading to the space formed by said enlarged 115 upper portion of the valve chamber.

3. A vaporizer for internal combustion 120 engines comprising a cylindrical valve casting having a fuel inlet at its lower end, a fixed cylindrical sleeve above said casting 125 having air ports, a movable cylindrical sleeve within said fixed sleeve having corresponding air ports, said movable sleeve having a closed bottom and a space beneath the 130

same for constant air supply, a cylindrical valve member depending from said movable sleeve into the valve casing and having a longitudinal fuel passage, and air ports leading from said fuel passage to said constant air supply space.

4. A vaporizer for internal combustion engines comprising a cylindrical valve casing having a fuel inlet at its lower end, a fixed cylindrical sleeve above said casing having air ports, a movable cylindrical sleeve within said fixed sleeve having corresponding air ports, said movable sleeve having a closed bottom and a space beneath the same for constant air supply, a cylindrical valve member depending from said movable sleeve into the valve casing and having a longitudinal fuel passage, air ports leading from said fuel passage to said constant air supply space, and means for simultaneously imparting both rotary and vertical movement to said sleeve and valve member.

5. A vaporizer for internal combustion engines comprising a cylindrical valve casing having a fuel inlet at its lower end, a fixed cylindrical sleeve above said casing having air ports, a movable cylindrical sleeve within said fixed sleeve having corresponding air ports, said movable sleeve having a closed bottom and a space beneath the same for constant air supply, a cylindrical valve member depending from said movable sleeve into the valve casing and having a longitudinal fuel passage, air ports leading from said fuel passage to said constant air supply space, means for imparting both rotary and vertical movement to said sleeve and valve member, and means for imparting vertical movement to said sleeve and valve member independently of the movement imparted by said first named means.

6. A vaporizer for hydrocarbon engines comprising a cylindrical valve casing having a fuel inlet at its lower end, a fixed cylindrical sleeve above said casing having air ports, a movable cylindrical sleeve within said fixed sleeve having coating air ports, said movable sleeve having a closed bottom and a space beneath for constant air supply a valve member for depending from said movable sleeve into said valve casing, and having fuel and air passages, means for rotating said movable sleeve, an adjusting sleeve rotatably held in fixed bearings and having inclined rib or screw connections with said movable sleeve, and means for turning said adjusting sleeve.

7. A vaporizer for internal combustion

engines comprising a mixing chamber having means for supplying air thereto, a pair of members of substantially cone shape spaced to admit a film of hydrocarbon therebetween, the upper of said members having an atomizing opening for injecting the combustible fluid into said chamber, means for admitting heating fluid to the interior of the lower member, and means for injecting a heated fluid other than air into said mixing chamber, substantially as described.

8. A vaporizer for internal combustion engines comprising a mixing chamber having means for supplying air thereto, a pair of members of substantially cone shape spaced to admit a film of hydrocarbon therebetween, the upper of said members having an atomizing opening for injecting the combustible fluid into said mixing chamber, means for supplying the heating fluid to the space beneath the lower cone shape member, and a passage for conducting the small quantity of heating fluid to the said mixing chamber.

9. A vaporizer for internal combustion engines comprising a valve chamber having a fuel admitting opening, a valve working in said chamber and having a central longitudinal passage therein, there being an annular air passage around a portion of the said valve and said valve having air passages leading from said longitudinal air passages to said annular chamber and said valve having also an auxiliary passage in proximity to said air passages, and means for supplying a heated fluid other than air to said auxiliary passage.

10. A vaporizer for internal combustion engines comprising a mixing chamber having means for supplying air thereto, a pair of members of substantially cone shape spaced to admit a film of hydrocarbon therebetween, the upper of said members having an atomizing opening for the passage of hydrocarbon to said mixing chamber, a valve controlling the passage of hydrocarbon to the mixing chamber, means for admitting heating fluid to the interior of the lower member, and means for conveying fluid from the interior of the lower member to the hydrocarbon prior to its entrance into the mixing chamber.

In testimony whereof, I affix my signature in the presence of two witnesses.
